(57) **CLAIM**

The ornamental design for an ashtray, as shown and described.

DESCRIPTION

FIG. 1 is a top, front and right side perspective view of an ashtray showing my new design;

FIG. 2 is a bottom, rear and left side perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof; and,

FIG. 8 is a bottom plan view thereof.

The broken lines immediately adjacent to the shaded surfaces depict the bounds of the claim and form no part of the claimed design. The unshaded surfaces between solid and broken lines in FIGS. 1 and 7 and all other broken lines in FIGS. 1-8 illustrate portions of the ashtray that form no part thereof.
